UNITED STATES PATENT OFFICE.

HAMILTON E. SMITH, OF NEW YORK, N. Y.

CLOTHES-SUPPORTING APRON FOR IRONING-MACHINES.

SPECIFICATION forming part of Letters Patent No. 230,900, dated August 10, 1880.

Application filed November 3, 1879.

To all whom it may concern:

Be it known that I, HAMILTON E. SMITH, of the city, county, and State of New York, have invented a new and useful Improvement 5 in Clothes-Supporting Aprons for Ironing-Machines, which improvement is fully set forth in the following specification, reference being had to the accompanying drawings, in which—

Figure 1 shows my apron partly in end view 10 and partly in section and without a surface-covering. Fig. 2 is a plan or top view thereof. Fig. 3 shows an end view with a surface-covering; and Fig. 4 shows a longitudinal section of one of the slats illustrated in Fig. 3, 15 the same being provided with a back slat and with a fibrous or textile surface-covering.

Similar letters indicate corresponding parts.

My invention relates to aprons for supporting or carrying the clothes around the cylinder in ironing-machines; and it consists in an apron constructed of a series of transverse metallic slats, which are connected together by hinge-joints, and have respectively a segmental cross-section, so that the apron readily 25 adapts itself to the surface of a cylinder. With the metallic slats are combined back slats of wood or like material for the purpose of giving the apron a substantially level surface or bearing, and also combined a fibrous 30 or textile surface-covering, the latter being thereby furnished with a rigid support.

In the drawings, the letter A designates the metallic slats, B the back slats, and C the surface-covering. 35 The metallic slats A extend transversely to the apron, and I prefer to make the same of brass or steel. To connect the slats A together, I use hinge-joints d, which in this example are formed by providing the slats with 40 knuckles upon their edges and fitting therein a suitable pintle, as clearly shown. I shape the slats A in cross-section so that each forms a segment of a circle corresponding to the surface of the cylinder over which the apron 45 is to pass. By hinging the slats A and shaping them in this manner the apron is caused to adapt itself to the ironing-cylinder in passing around it, as indicated in the drawings, Fig. 1.

50 When the apron is used on a machine for ironing cuffs, collars, or other articles intended

to receive a polish or gloss on both sides, I omit the surface-covering C and polish the faces of the slats A, and by this means the apron is adapted to act in conjunction with 55 the cylinder of the machine for polishing both sides of an article.

The back slats, B, are of less width than the metallic slats A, and are fastened by rivets e or other suitable means, the same being in this 60 example made of wood, and being, moreover, shod with sheet metal to protect the same against wear. I usually make the back slats, B, of a tapered form in cross-section, and so that the widest portion thereof fits between 65 the hinge-joints d. In this manner the back slats, B, are allowed to fold together as the apron passes around the rollers of the ironing-machine before and after it passes around the cylinder; but the same result can be attained 70 by making the back slats of narrow width.

The main office of the back slats is to render the under surface or bearing of the apron level, and to this end the slats are made of such thickness that the lower level or plane thereof 75 is below the hinge-joints d.

The surface-covering C is used when it is desired to give the apron a frictional surface, and it is composed of a layer of felt or other fibrous or textile material. 80

For the purpose of fastening the covering C, I use double-pointed tacks f, which are embedded in the covering and driven through the metallic slats A into the back slats, B, so that the top of the covering remains level or 85 unaffected thereby; but the covering can be fastened in various other ways with a like result. What I claim as new, and desire to secure by Letters Patent, is—

1. An apron for ironing-machines, consisting 90 of a series of transverse metallic slats, which are connected together by means of hinge-joints, and have respectively a segmental cross-section, substantially as and for the purpose described.

2. An apron for ironing-machines, consisting 95 of a series of transverse metallic slats, which are connected together by means of hinge-joints, and have respectively a segmental cross-section, combined with back slats of wood or 100 like material, substantially as and for the purpose described.

3. An apron for ironing-machines, consisting of a series of transverse metallic slats, which are connected together by means of hinge-joints, and have respectively a segmental cross-section, combined with a fibrous or textile surface-covering, substantially as and for the purpose described.

In testimony that I claim the foregoing I have hereunto set my hand and seal this 1st day of November, 1879.

HAMILTON E. SMITH. [L. S.]
